Patented Jan. 3, 1922.

UNITED STATES PATENT OFFICE.

JESSIE W. FELKNER, OF IOWA CITY, IOWA.

DOLL STRUCTURE.

1,402,345.

Specification of Letters Patent.

Patented Jan. 3, 1922.

Application filed March 10, 1921. Serial No. 451,277.

To all whom it may concern:

Be it known that I, JESSIE W. FELKNER, a citizen of the United States, residing at Iowa City, in the county of Johnson and 5 State of Iowa, have invented certain new and useful Improvements in Doll Structures; and I do hereby declare the following to be a full, clear, and exact description of the invention, such as will enable 10 others skilled in the art to which it appertains to make and use the same.

This invention relates to improvements in the manufacture of dolls, and particularly embodies certain structural characteristics, 15 as will hereinafter appear, together with an improved method of carrying forward the same.

Although some of my improved features may well be employed with types of dolls 20 other than those commonly designated as rag dolls, and hence I do not specifically limit the general application of my improvements, still the invention as a whole has been more particularly devised with especial reference 25 to providing a comparatively indestructible rag stuffed doll, that is unaffected by ordinary heat and moisture, and one which is formed with pliable imitation flesh portions, including the face, neck, shoulders, chest 30 and upper back portions, the face being artistically hand painted with a personal touch to lend individuality to each doll, while the pliability of the face structure, in conjunction with its hand painting, will impart a 35 more or less mobile appearing countenance or animated life-like expression.

In addition to the foregoing and other objects and advantages, which will clearly appear as incidental to the following disclosure, further important features may be emphasized at the outset as embodying the particular mode of attaching the wig, the soft background packing for the pliable face, 40 the internal neck support extending between the head and upper body trunk, the particular formation of the face and other pliable imitation fleshy portions, and the method of assembling, securing together and stuffing the parts.

With these prefacing remarks, reference 45 will now be immediately had to the accompanying drawings, illustrating practical embodiments of the improvements, in which drawings—

55 Figure 1 is a side elevational view of a

rag stuffed doll embodying my improvements, the wig being shown as braided, although it may be bobbed, and a bang-strip being illustrated forwardly of the wig proper; Figure 2 is a sectional view on an 60 enlarged scale, taken in a vertical plane extending forwardly and rearwardly, and also illustrating a special seat flap for stuffing purposes; Figure 3 is a side elevational view of the upper portion of the doll, partly 65 broken away sectionally, the hair of the wig being shown as close cut; Figure 4 is a fragmentary sectional view taken along the line 4—4 of Figure 3; and Figure 5 is a cross-sectional view along the line 5—5 of 70 Figure 1, with the bottom closure flap shown as partially open.

Before describing other important features, I will first refer to the casing elements for the trunk of the body and the dummy 75 head at the rear of the face portion, just as they are illustrated although I do not restrict myself to all of the details as shown.

These casing elements may be front and rear patterned sections 10 and 11, that are 80 stitched together up the sides, as at 12, and provide a normally open bottom.

Each casing section is formed of a plurality of layers of suitable fabric, two such layers being shown, and of which the inner 85 layer may be of substantially heavier texture than the outer layer, which latter is in the nature of a finishing layer.

As seen at 13, the stuffed legs 14 are stitched to the lower front section and also 90 as seen at 15, a bottom flap closure 16 is stitched at its forward edge to the front section along the upper rear edges of the legs, the flap being adapted to be left otherwise unsecured until the body is stuffed, 95 after which it is stitched to the rear section as indicated at 17.

The inner layer of the rear section 11 may be continued as an upward extension 18 that is adapted to terminate at the rear of 100 the forehead, while the outer layer of the rear section is likewise continued as an upward extension 19 that may terminate short of the extension 18. In an analogous manner 20 and 21, respectively, may be 105 shorter and longer upper forward extensions of the front section 10, that are adapted to overlap the associated ends of the layers 18 and 19, as shown more clearly at Figure 2, and which are adapted to be finally 110

secured together, as would be indicated by the lines of stitching 22 and 23, as indicated at Figure 3.

The upper front layer section 20—21, behind the face portion as will later appear, does not form an immediate backing for said face portion, but provides a distinct front head chamber 24, to receive a soft packing material such as raw cotton or the like, and 10 a rear head chamber 25 which may be packed with soft rags or other suitable material, while the bust chamber 26 is likewise packed with such a soft rag or analogous filling.

27 indicates an internal support extending through the bust chamber 26 and well up into the rear head chamber 25, which internal support is shown as being enveloped with a spirally wrapped fabric covering 28. This internal support is shown as 15 a clothes-pin, and the structure of a clothes-pin may have its advantages, but obviously any other suitable form of internal support would suffice. The functioning of all of the foregoing, however, will later appear 20 more clearly.

The body trunk casing provides an elongated chamber 30 that may be filled with sawdust, and if desired a lower packing of rags or other material 31 may be employed, 30 which is finally bottomed by the closure flap 16.

The face, chest, front neck and shoulders and the upper bust portions may be integrally formed of alternate layers of paper and fabric, having an exterior coating of 35 paint and finishing enamel. In the drawings only three such layers of paper and fabric are illustrated, the intermediate layer 32 being paper, while the outer and inner 40 layers 33 are of fabric, and the paint or enamel exterior coating is indicated at 34. In actual practice, however, there may be more layers, if desired, and the extreme inner layer should be of paper, all of which 45 will fully appear later on.

The actual thickness of all layers are naturally exaggerated for clearness of illustration in section, and in forming the face section the upper edge portion of the outer 50 fabric layer 33 may be a little longer than the other layers to provide a marginal lap or strip 35, that is adapted to lap over and be secured to the fabric sections 18—20—21, while the lower edge portion of the outer 55 fabric 33 may also be a little longer, if desired, to be turned in behind the inner layer, as would be indicated at 36.

Analogously the rear neck and shoulders, and the upper back, are formed of layers 60 of paper 37, fabric 38 and an exterior coating of paint and finishing enamel 39, it being understood that the front and rear sections are adapted to be stitched together as at 55, with the stitching later covered

by the extending side marginal flap 35 and 65 a final coating of enamel or paint. Also the sections provide complementary arm pit openings, as will be obvious, for receiving the flexibly suspended arms, the forearms and hands of which may be of enameled 70 form as indicated at 40, with the upper stuffed section 41 flexibly hung from the arm pits.

42 simply indicates a finishing band of 75 flexible enameled fabric that extends around and covers the joinder of the upper sections with the trunk, while 43 analogously indicates a finishing enameled strip extending contiguously around the arm pit openings.

With the finer types of rag dolls, and with 80 other forms of dolls, that are provided with wigs, one of the main objections thereto has been the difficulty of so applying the wig that its hair could be combed in a natural way and without tearing the wig to pieces. 85

One of the most important features of my improvements resides in the novel manner of attaching a wig that will be free from the objections heretofore encountered.

With this end in view, I preferably make 90 the wig in two sections, indicated at 45 and 46, the outer edges of which are turned under as at 47 and 48, and the inner edges of which are contiguously disposed as at 49, and by this arrangement it will be seen that 95 the hair will appear as a natural outgrowth from the scalp as would be indicated at 50 and 51. As a matter of illustration only, I have also shown a bang-strip 52 immediately anterior of the wig section proper, and 100 likewise a posterior strip 53 at the rear base of the section 46, but it will be understood that these are not at all essential to the primary invention.

As has been before stated, the face, the 105 bust and intermediate front portions may be integrally formed of alternate layers of paper and fabric having an exterior coating of paint and finishing enamel, and this may be accomplished substantially in the 110 following manner:—

First there is placed over a mould-form, of any suitable type, a layer of wet thin paper, such as strong tissue paper which is firmly smoothed over the face of the mould-form with a damp cloth to work out all of the wrinkles. I then apply a layer of suitable fabric, preferably soft muslin which should be very pliable or exactly bias so that it can be smoothly applied over the 115 paper layer. This piece of fabric is preferably cut to provide slight gashes in the cloth, and a triangular bias piece is particularly suitable, whereby a smooth fit is assured around the ears and under the chin. 120

During these steps the fabric and paper layers are maintained thoroughly wet. Another coating layer of uncooked flour paste,

or its equivalent, is then applied and these successive layers are alternately repeated until the several layers appear to be sufficiently stable to absorb and hold the outer 5 coating of paint.

As a matter of fact shellac may also be employed, if needed, but this is not strictly essential and it is believed that the face and bust portions are more pliable, or life-like 10 in appearance when stiffening shellac is not used.

The mold may then be temporarily laid aside to allow the applied layers to become thoroughly dried and set, after which the 15 exterior layer may be painted with any suitable number of coats of paint, the last one of which should be of a flesh colored tint. Finally there may be applied a coating of tinted enamel, after which such features as 20 the eyes, eyebrows and eyelashes, may be applied, and the lips and cheeks tinted for properly bringing out a more natural expression.

As a matter of fact the painting of the 25 face and its integral portions may be done before or after applying the wig, as later referred to, but it is believed to be best to paint the face last, so that there will be less chances of marring the features, it being 30 understood that these doll features should be as varied and original in type as those of little children.

The rear half section of the upper part 35 of the body, as indicated by the layers 37—38—39, is formed in the same manner and requires no specific description. This is also true with reference to the painting and 40 enameling of the forearm and hand sections.

In applying the wig to the face portion, 45 the forward edge of the section 45 is first stitched around the marginal flap 35 of the face, as would be indicated at 47, and is adapted to be folded back rearwardly over the edge portion 47.

Although not essential to the invention at 50 all, it may be said that it is necessary to protect the hair of the wig from the paint applied to the face. To do this, I mark a hair-line, around the forehead and behind 55 the ears, as a guide for sewing on the wig. I then sew over this a piece of paraffin paper, sufficiently large to fold back with the wig. The wig is then securely stitched on in position, to be turned back from the face as heretofore described. When the face 60 has been painted, and after the paint has become dried, this paraffin paper can readily be torn away.

The rear upper body section may also be 65 formed with a marginal flap of fabric, analogously to the flap 35, to which the rear marginal edge of the wig section 46 may be stitched, as indicated at 48, it being understood that the sections 45 and 46 are adapted

to be folded over towards each other and 70 stitched along their contiguous edges as at 49.

Without considering the bang-strip 52 or rear base strip 53, it will be seen at 50 and 75 51 that the hair of the wig, along these positions, appears as a natural outgrowth from the scalp, and can be combed in any direction the same as natural growing hair, without the comb engaging underneath and displacing the imitation scalp section of the 80 wig.

There may be several ways of assembling 85 the doll structure as a whole and in some cases, for instance, the front and rear upper sections might be stitched together along the 90 line 55, and sewed to the trunk body section as a unit, whether of a full stuffed or hollow formation and whether or not a soft cotton background for the face portion was employed.

I shall, however, specifically describe the 95 exact building up of the doll as shown in the drawings by way of illustration.

We will assume that the face section and 100 the rear upper section have been properly 95 molded and are to be now applied to the trunk body portion.

The lower edge of the bust portion is 105 stitched around the front section of the body casing with the finishing front band 95 42. A soft packing material may then be placed inside the molded face portion, as indicated at 24, then the extension layers 20 and 21 may be stitched together and to the marginal flap 35, underneath the latter. In 110 an analogous manner the rear upper section may be stitched to the trunk portion with the rear finishing band 42, the extensions 18 and 19 being properly secured by stitching and closing up the back of the 115 head, as heretofore referred to and which will be self apparent from the illustrations.

The rear head chamber 25 could be partially stuffed before the extensions 18 and 120 19 are stitched in place, but it would be just 110 as easy to stuff the interior by way of the trunk portion.

The rear head chamber having been substantially stuffed with a rag packing or the like, it will be seen that the extension layers 125 20 and 21 function as a membrane which is forced with an even pressure towards the molded face portion, for packing the soft cotton in the chamber 24 snugly up against the rear of the face portion as a pliable 130 backing therefor.

When the chamber 25 has been substantially packed, there may be wedged up into the packing the upper end of the internal support 27, around which there has first 135 been spirally wound a cloth covering 28, functioning as an additional filling. This not only aids in packing the rags in the head

chamber 25, but it also serves as an internal support longitudinally of the neck between the bust and the head portions, providing for a limited play or flexible movement of 5 the head and neck with reference to the body portion. Even though a clothes-pin be employed for this support, it may be more desirable to have its upper end beveled or cone-shaped instead of as shown.

10 The bust portion may then be packed with rags or the like around the lower end of the internal support, as would be indicated at 26, and if a neck support analogous to a clothes pin is used, a wedging element, not shown, could be inserted between its bifurcated arms, for spreading them apart slightly to make the stuffing 26 even more compact, if desired, after initial packing home.

15 20 The trunk-body chamber 30 may then be filled with sawdust, or other filling material, which may be finally bottomed by a rag packing 31 that is held in place by the closure flap 16, which latter is then secured as by the stitching 17.

Finally, it may be said that the wig is preferably formed from the silk-like coats of longhaired animals, such as Angora goats or the like.

25 30 It is believed that the advantages of all of the foregoing features will be quite apparent to those who are familiar with the desires of children towards more human-like dolls, as well as to those who understand the necessity for making such dolls as indestructible as reasonably possible.

While I have thus disclosed certain preferred embodiment of my invention, it may later be found to be expedient or desirable to make some alterations in the structural form and arrangement of the parts, but without departing from the spirit of the invention, and it will be understood, therefore, that I do not necessarily restrict myself to all of the details exactly as disclosed, excepting as they may come within the terms of the ensuing claims, when fairly interpreted in the light of the specification, if necessary, or equivalent features.

50 What I do claim, as new and patentable, is—

1. A doll structure, providing a lower flexible body casing, adapted to be stuffed, 55 and normally open at its bottom for the insertion of the stuffing material, legs attached to said casing forwardly of said bottom opening, and a flap so dimensioned and secured along its forward edge as to extend 60 rearwardly below said opening as a closure therefor, with the remaining edge of said flap secured around the rear bottom edge of said casing, substantially as described.

2. A doll structure, providing a normally

65 hollow head and a pliant face portion, the said hollow head having a transversely disposed flexible partition, forming a restricted forward chamber, encompassing the rear of said face portion, and a larger rear chamber, a soft packing material filling 70 said forward chamber as a pliant backing for said face portion, and a filling material packed in said rear chamber, for filling the latter and also uniformly pressing said flexible partition up against said soft packing material contained in said forward chamber, substantially as described.

75 3. A doll structure, providing a normally hollow head, a lower flexible body casing 80 adapted to be stuffed, and a pliantly formed face, neck and bust section, the front of said flexible body casing being extended upwardly to provide a flexible partition transversely disposed within said hollow head to form a restricted forward chamber, encompassing the rear of said face portion, and a larger rear chamber, a soft packing material filling 85 said forward chamber as a pliant backing for said face portion, and a filling material packed in said rear chamber and up against said flexible partition, substantially as described.

90 4. A doll structure, providing a normally hollow head, a lower flexible body casing 95 adapted to be stuffed, and a pliantly formed face, neck and bust section, which section is built up of alternate layers of paper, freely porous cloth fabric and a pasty binder substance, the section being exteriorly coated 100 with paint and a finishing enamel and the organs and features of expression being hand painted thereon, a flexible partition transversely disposed within said hollow head and forming a restricted forward chamber, encompassing the rear of said face 105 portion, and a larger rear chamber, a soft packing material filling said forward chamber as a pliant backing for said face portion, and a filling material packed in said rear chamber and up against said flexible partition, substantially as described.

110 5. A doll structure, providing a normally hollow head, a lower flexible body casing 115 adapted to be stuffed, and a pliantly formed face, neck and bust section, which section is built up of alternate layers of paper, fabric and a pasty binder substance, the section being exteriorly coated with paint, tinting coloring and a finishing enamel, and the organs and features of expression being hand painted thereon, a flexible partition transversely disposed within said hollow head and forming a restricted forward chamber, encompassing the rear of said face portion, and a larger rear chamber, the said flexible partition comprising an upwardly extended 120 continuation of the front of said lower flexible body casing, a soft packing material fill- 125

ing said forward head chamber as a pliant backing for said face portion, and a filling material packed in said rear head chamber and up against said flexible partition, substantially as described.

6. A doll structure, providing a normally hollow head, a lower flexible body casing adapted to be stuffed, and pliant upper back, bust, neck and face portions, formed 10 of alternate flexible layers of suitable material and a pasty binder substance, suitably molded into shape, which portions are suitably coated exteriorly with paint and a finishing enamel, and the organs and features 15 of expression of the face being hand painted thereon for giving individuality thereto, a flexible partition transversely disposed within said hollow head and forming a restricted forward chamber, encompassing the rear of 20 said face portion, and a larger rear chamber, a soft packing material filling said forward chamber as a pliant backing for said face portion, a filling material packed in said rear chamber and up against said flexible

partition, and an internal support extending 25 through said neck portion and projecting substantially within said head and bust portions, substantially as described.

7. In doll structures, the method of applying a wig on the head thereof, which consists in first securing the outer marginal edge of the wig to the head, turning the body portion of the wig inwardly over said marginal edge, and finally securing the body portion of the wig to the head portion also, 30 substantially as set forth.

8. In doll structures, the method of applying a wig on the head thereof as forward and rear sections, which consists in initially securing the outer marginal edge 40 of the wig to the head with the hair side down, turning the body portion of the wig inwardly over said marginal edge, and finally securing the free edges of the wig sections relatively to the head portion, sub- 45 substantially as set forth.

In testimony whereof, I affix my signature.
JESSIE W. FELKNER.
